UNITED STATES PATENT OFFICE.

THOMAS QUINN, OF HUNTINGTON, WEST VIRGINIA.

EXTENSION-RAIL.

1,392,353.

Specification of Letters Patent. Patented Oct. 4, 1921.

Application filed April 12, 1920. Serial No. 373,246.

To all whom it may concern:

Be it known that I, THOMAS QUINN, citizen of the United States, residing at Huntington, in the county of Cabell and State of West Virginia, have invented certain new and useful Improvements in Extension-Rails, of which the following is a specification.

This invention relates to an improved extension rail for mine tracks and has as one of its principal objects to provide a device of this character whereby the rails of a mine track may be readily lengthened or shortened at the working face of the mine.

The invention has as a further object to provide an extension rail having a bumper so that a mine car can not run off of the end of the track at the working face of the mine.

And the invention has as a still further object to provide an extension rail which may be readily employed in connection with the ordinary T-shaped track rail and which may also be used in connection with substantially any conventional type of tie.

Other and incidental objects will appear hereinafter.

In the drawings:

Figure 1 is a fragmentary side elevation showing my improved extension rail in position upon an ordinary mine track rail,

Fig. 2 is a plan view similar to Fig. 1,

Fig. 3 is a fragmentary perspective view particularly showing the inner end portion of the extension rail, and

Fig. 4 is a transverse sectional view on the line 4—4 of Fig. 2, looking in the direction of the arrows.

As is well known, considerable difficulty is at present experienced in shortening and lengthening the track of a coal mine at the working face of the mine. Where a cutting machine is used, a portion of the track adjacent the working face of the mine must be torn up so as to make room to unload the machine and after a cut has been made, the track must be again relaid. As will be perceived, much valuable time is, therefore, lost in thus tearing up and relaying the track and, of course, considerable expense is also incurred. The present invention, therefore, seeks to overcome the difficulties mentioned as well as to provide an extension rail which, in addition to eliminating the necessity for tearing up the mine track, will also possess other advantages tending toward the complete efficiency of the rail.

Referring now more particularly to the drawing, I have shown my improved extension rail in connection with an ordinary mine track rail 10, this rail being of the usual T-shape in cross section and being spiked or otherwise secured to the track ties 11. These ties have also been conventionally shown. The rail of the present invention is formed to slidably fit freely over the rail 10 and is constructed with a hollow tread 12 fitting around the tread of the rail 10 and provided with confronting side flanges 13 engaging opposite sides of the track rail web. At the lower edges of the flanges 13 of the extension rail are divergent base flanges 14 seating against the upper face of the base flange of the rail 10. The tread, side and base flanges of the rail are preferably formed as an integral structure and at its inner end the tread is, as particularly shown in Fig. 3, provided with beveled faces 15 sloping to the upper face of the tread of the rail 10 so that the wheels of rolling stock will pass from one rail to the other without jolting. Fitted into the outer end of the extension rail is one end of an upwardly directed bumper 16. This bumper may be formed from a section of ordinary T-rail properly bent and engaged through the side flanges of the extension rail and through the inner end of the bumper are bolts or other approved fastening devices 17 firmly securing the bumper and rail together. However, if preferred, the bumper and rail may be formed as an integral structure but in any instance where the bumper is secured in the outer end of the rail, as shown in the drawing, the outer end of the tread of the extension rail will be provided with beveled faces 18 similar to the faces 15 of said rail and designed to serve a similar function. Formed through the side flanges of the extension rail throughout the major portion of the length thereof, are spaced pairs of registering openings 19 which are arranged to be brought into register with the usual bolt openings through the forward end portion of the rail 10 and engaged through registering openings of the rails are bolts or other approved fastening devices 20 firmly securing the rails together, it being observed in this connection that the extension rail may be adjusted along the track rail and bolted in adjusted position. When the extension rail is thus in place, additional track ties 21, similar to the ties 11, are arranged therebeneath for supporting

the outer end portion of the extension rail thereon, the extension rail being spiked or otherwise secured to such ties. As will, of course, be understood, one of the extension rails with its bumper is used in connection with each rail of a mine track so that by positioning the extension rails forwardly to extend to the working face of the mine, as suggested in the drawing, a car upon the mine track may be rolled onto the extension rails to closely approach said face in convenient position for loading. At the same time, the bumpers 16 will positively obviate the possibility of the car running off of the track.

As will now be readily appreciated in view of the preceding description, when the bolts 20 are removed, the extension rail may be slid rearwardly over the track rail 10. Consequently, a mine track equipped with a pair of my improved extension rails may be readily shortened away from the working face of the mine and may as easily be again extended. I accordingly provide a particularly effective construction for the purpose set forth and, as will be noted, an extension rail which may be readily employed in connection with substantially any conventional type of mine track rail. Further, the extension rail may be used in conjunction with either a steel tie or a wooden tie.

Any difference in the gage of the track created by the use of the extension rail may be readily overcome by simply spreading slightly the track rails 10.

Having thus described the invention, what is claimed as new is:

1. An extension rail formed to slidably fit

over a track rail for adjustment longitudinally thereon and provided with longitudinally spaced means whereby the extension rail may be secured to the track rail in adjusted position longitudinally of the track rail.

2. An extension rail formed to slidably fit over a track rail and provided at one end 45 with a bumper engageable with the track rail for limiting the extension rail in its movement inwardly over the track rail.

3. An extension rail formed to snugly receive a track rail therein slidably coating 50 with the track rail and provided at its outer end with a bumper, the extension rail being formed with openings for selectively receiving a fastening device whereby said rail may be secured in adjusted position longitudinally of a track rail.

4. In a device of the character described, the combination of an extension rail formed to slidably fit over a track rail, and a bumper carried by the extension rail.

5. The combination with a track rail, of an extension rail slidably fitting over the track rail, and a bumper carried by the extension rail, the extension rail being adjustable longitudinally upon the track rail 65 whereby to shift said bumper and adjustably locate the effective end of the track rail.

6. A device of the character described including an extension rail open at its lower side and formed to snugly fit the ball and web of a track rail and resting against the base flange of the track rail.

In testimony whereof I affix my signature.

THOMAS QUINN. [L. s.]
